(57) **CLAIM**

I claim the ornamental design for a band clamp for mounting an animal guard, as shown and described.

DESCRIPTION

FIG. 1 is a front perspective view of a band clamp for mounting an animal guard according to my new design; FIG. 2 is a rear perspective view thereof; FIG. 3 is a front elevation view thereof; FIG. 4 is a rear elevation view thereof; FIG. 5 is an end view thereof; FIG. 6 is an opposite end view thereof; FIG. 7 is a top plan view thereof; FIG. 8 is a bottom view thereof; FIG. 9 is a first environmental view of the band clamp for mounting an animal guard, shown wrapped around a post or pole, and in use with an exemplary squirrel baffle in a first position in relation to the assembled clamp; FIG. 10 is a second environmental view thereof, wherein the exemplary baffle is in a second position in relation to the assembled clamp; and, FIG. 11 is a last environmental view thereof, wherein the exemplary baffle is in a third position in relation to the assembled clamp. The broken lines in FIGS. 9–11 illustrate environmental structure and form no part of the claimed design.
